UNITED STATES PATENT OFFICE.

ERNEST COBURN, OF RACINE, WISCONSIN, ASSIGNOR TO J. I. CASE THRESHING MACHINE COMPANY, OF RACINE, WISCONSIN, A CORPORATION.

COMBINATION HARVESTER THRASHER.

Application filed February 18, 1924. Serial No. 693,441.

To all whom it may concern:

Be it known that I, ERNEST COBURN, a citizen of the United States, residing at Racine, in the county of Racine and State 5 of Wisconsin, have invented certain new and useful Improvements in Combination Harvester Thrashers, of which the following is a specification.

My present invention relates to improvements in combination harvester-thrashers of the character disclosed in Letters Patent No. 1,498,354 issued June 17, 1924, upon my application and particularly to the mechanism for connecting the leveling wheel to the 15 thrasher whereby I provide a yielding and stable means for the purpose which positively control the variable movement of certain parts of the machine, all as will be hereinafter more fully explained.

20 In the accompanying drawings, forming part hereof, Figure 1 is a rear elevation of a harvester-thrasher embodying my invention; Fig. 2 a plan of the improved flexible connection which I employ; Fig. 3 a transverse sectional view of the stub axle and parts associated therewith; Fig. 4 a fragmentary side elevation of the thrasher showing the rackbar and associated parts; Fig. 5 a plan of the thrasher and my improved 25 flexible connection; and Fig. 6 is a detail rear elevation indicating in full and dotted lines the range of adjustment of my improved flexible connection.

In said drawings the portions marked 30 5 indicate the thrasher mounted upon an axle, 6, which supports a bull-wheel, 7, the harvester or header, 8, being supported from the axle, 9, which is provided with a grain wheel, 10, at its outer end, and at its inner 35 end is flexibly connected to a stub axle, 11, for supporting a leveling wheel, 12, all of which elements are described in the patent herein referred to.

Upon said axle 11 I provide a sleeve, 14, 40 45 embodying an upwardly projecting bracket, 15, for supporting a rackbar, 16, of any desired or well known construction, the upper part of which engages actuating mechanism, 17, which is supported from the thrasher 50 housing in a well known manner. The outer end of axle 11 is provided with a brace, 18, secured thereto by a set screw 18' the upper end of which is secured to said rackbar 16 for stabilizing the same. In said axle 11

I insert a rotatable connecting member, 20, 55 having a neck, 21, near its inner end about which I position a split collar, 22, through which and the axle 11 and sleeve 14 registering holes are provided in which screw bolts, 23, are inserted for securing said parts 60 together, the head, 20', of member 20 preventing the same from being withdrawn, the outer horizontal portion of said connecting member being mounted in a bushing, 24, secured thereto by a set screw 24', all 65 as is clearly shown in Fig. 2. A similar connecting member, 26, is rotatably mounted in axle 6, the arm, 27, of which is considerably longer than the arm 28 of member 20, the ends of said arms being pivotally 70 connected by a bolt, 29, or otherwise. Said member 26 is mounted in a bushing, 30, secured thereto by a set screw 30' and its inner end is provided with a neck, 31, and head, 32, and is held in position by a split collar, 75 33, and screw bolts, 34, in a manner similar to member 20.

As is well known in practice, combination harvester-thrashers occupy considerable ground space and in traveling are subjected to irregular movements in relation to each other because of the constantly changing ground irregularities, and it is highly important that the movements of the leveling wheel shall at all times harmonize with 80 those of the thrasher without liability of unduly straining the connections between them.

In the operation of such machine with my improvements embodied therein the scissors-like connecting members 20 and 26 being 90 both pivotally mounted as shown are highly sensitive to the irregular movements of the wheels 7 and 12, and when there is the slightest variation in their relative movements the horizontal portions of the connecting members will rotate, carrying their arms 27, 28, in the same direction, but as one of said arms is shorter the range of movement thereof is such that when leveling wheel 12 travels over ground higher or 100 lower than that upon which wheel 7 is moving the absolute perpendicular position of rackbar 16 is maintained during its elevation and descent without any tendency of binding in its actuating mechanism, which 105 has been a troublesome defect experienced in the operation of harvester-thrashers, and by so controlling the free movement of said

rackbar at all times such objection is overcome. As indicated by the full and dotted lines in Fig. 6, the peculiar connection produced between arms 27, 28, constantly control the vertical movements of rackbar 16 either in slight or extensive ranges of movement of the wheel 12, and at all times respond to the variable ground level of said wheel. It will be understood also that the 10 horizontal portions of the connecting members being locked against endwise movement prevent tilting of the leveling wheel, and the connected thrasher and harvester sections are further held in flexible relation 15 by stay bars, as 37, 38, in a well known manner.

I claim as my invention:

1. In a machine comprising a harvester and a thrasher, an axle on said thrasher, a 20 connecting member mounted in said axle, a leveling wheel for said harvester having an axle, a connecting member in said harvester axle, and means for securing said members together.

2. In a machine comprising a harvester and thrasher, a swivelled connecting member supported by said thrasher and having an arm, a leveling wheel for said harvester, a swivelled connecting member supported by 30 said wheel and having an arm, and means for securing said arms to permit the movements thereof during the traveling operation of said wheel.

3. The combination, with a harvester-thrasher comprising a thrasher section and a harvester section, of connecting members associated with said sections, an arm on each of said members extending at right angles therefrom, and means for pivotally connecting 35 said arms together.

4. The combination, with a harvester-thrasher comprising a thrasher section and a harvester section, each of said sections having an axle, of connecting members embodying arms associated with said axles, said arms extending at right angles from 45 said members, means for permitting the variable movement of said members, and means for pivotally connecting said arms

to permit the movement of said members in relation to each other.

5. In a machine comprising a harvester and thrasher, a swivelled controlling member connected to said harvester, an arm on said member arranged at right angles in 55 relation thereto and movable therewith, a swivelled member connected to said thrasher, an arm on said member arranged at right angles thereto and movable therewith, and means for pivotally connecting said arms at 60 their ends.

6. In a combination harvester-thrasher, the combination of a leveling wheel having an axle, a swivelled connecting member supported by said axle, means associated with 65 said axle for preventing endwise movement of said member, and means for pivotally connecting said member to said thrasher.

7. In a combination harvester-thrasher, the combination of a leveling wheel having an axle, a connecting member supported by 70 said axle and having a neck, a collar about said neck, means for securing said axle and collar to prevent endwise movement of said member, and means for yieldingly connecting said member to said thrasher.

8. In a combination harvester-thrasher, the combination of a leveling wheel having an axle, a rackbar mounted thereon, a connecting member supported by said axle, a 80 thrasher axle, a connecting member mounted in said axle, and means for connecting said members.

9. In a machine comprising a harvester and thrasher, a swiveling connecting member supported by said harvester, an arm on said member positioned at right angles thereto, means for preventing endwise movement of said member, a swiveling connecting member supported by said thrasher, an arm on said member positioned at right angles thereto, means for preventing endwise movement of said member, and means connecting said arms to permit their simultaneous uniform movement or independent variable movement in relation to each other.

In testimony whereof I affix my signature.
ERNEST COBURN.
